(57) **CLAIM**

The ornamental design for a camera carrier, camera sling, camera holder, and/or camera cover, as shown and described.

DESCRIPTION

FIG. 1 is a front perspective view of a camera carrier, camera sling, camera holder, and/or camera cover showing my new design;

FIG. 2 is a rear perspective view thereof;

FIG. 3 is bottom view thereof;

FIG. 4 is top view thereof;

FIG. 5 is a front view thereof; and,

FIG. 6 is a rear view thereof.

The portions deemphasized with relatively light transparent gray overlay depict portions of the camera carrier, camera sling, camera holder, and/or camera cover which form no part of the claimed design.

1 Claim, 6 Drawing Sheets
